UNITED STATES PATENT OFFICE.

OWEN MARSHALL JONES, OF NEW YORK, N. Y.

VALVE.

1,364,059.

Specification of Letters Patent. Patented Dec. 28, 1920.

Application filed January 9, 1917. Serial No. 141,416.

To all whom it may concern:

Be it known that I, OWEN MARSHALL JONES, a citizen of the United States, and a resident of the borough of Manhattan, city, 5 county, and State of New York, have invented certain new and useful Improvements in Valves, of which the following is a specification accompanied by drawings.

The invention relates to improvements in 10 valves, but in particular to improvements in valves commonly known as stop valves which are used for stopping or retarding the flow of fluids through ducts in which the valves are placed or to which the valves 15 are connected, although the invention may be used in any connection in which it is found applicable.

The objects of the invention are to improve upon and simplify the construction of 20 such valves and to increase their efficiency.

Other objects of the invention are to insure tight seating valves.

Further objects of the invention are to supply valves which will become tighter the 25 longer they are in use by having the valves self-grinding against the seats, thereby reducing to a minimum the possibility of leaks through the valves; and to these ends the invention consists of apparatus and devices 30 for carrying out the above objects embodied in a valve having the features of construction, combinations of elements, and arrangement of parts, substantially as hereinafter fully described and claimed in this specification, and shown in the accompanying drawings, in which—

Figure 1 is a longitudinal sectional elevation of one form of the apparatus embodying the invention.

40 Fig. 2 is a transverse section of the valve body through line A—B of Fig. 1.

Fig. 3 is a plan view of a valve seat protecting plate.

Referring to the drawings, in Fig. 1, I 45 have shown an illustrative embodiment of the invention. This view shows the valve open. 2 and 2^a represent the body, which may be of any suitable metal and which is in two sections properly held together, thus 50 forming the body. 3 is the valve seat against which the valve disk 4 seats. 6 and 6^a are ports through the valve disk which register respectively with the apertures 5 and 5^a in the seat to allow flow of fluid 55 through the valve. 7 is the inlet to the body. 8 is the outlet of the valve body. 9 is a

stem extending from the valve disk with a transverse slot in the outer end. 24 is a barrel extending into the chamber of the valve body section 2^a. This barrel may be 60 an integral part of the valve body section 2^a as shown or a separate barrel inserted through the wall of the body. This barrel protects the stems 10 and 9 from corroding or pitting elements. One end of the barrel 65 24 enters at the center portion of the valve seat 3 and this seat 3 is held in place by the overlapping of the flange on the larger end of the valve body section 2. 10 is a stem extending through the barrel 24 with a flat 70 reduced section at the inner end to be engaged by the slot in the stem 9. The stems 10 and 9 comprise the operating stem. 26 is an enlarged portion of the stem 10 and it is beveled on one side to fit in a corresponding bevel in the bottom of the barrel 24, thereby making a seat joint to prevent 75 leakage around the stem 10 where it passes through the valve body. The enlarged portion 26 is for emergency only in case there 80 might be slight leakage between the seat and the disk of the valve and into the barrel around the stem 9. 16 is a spring placed around the stem 10, one end bearing on the body 2^a and the other end bearing against 85 the collar 14, the collar being held in place on the stem 10 by the set screw 15, the collar being placed so that the spring is compressed, thus holding the beveled portion 26 90 against its seat. 13 is a handle acting as a lever for revolving the valve disk.

The operation of the valve is as follows: The valve as shown is open and allows the fluid to pass through. To stop the flow of the fluid the lever 13 is revolved, which in 95 turn revolves the stems 10 and 9 forming the operating stem, which revolves the disk 4 which moves the ports 6 and 6^a out of register with the apertures 5 and 5^a, thereby stopping the flow of the fluid. Naturally 100 the reverse action of the lever again places the ports in register with the apertures. The fluid from the inlet side exerts a pressure on the back of the disk 4, thereby holding it tight against the seat 3 so that the 105 fluid will not leak through the apertures in the seat 3. When the valve is in use, pressure is maintained on the back of the disk 4, so when the disk 4 is revolved to open the valve, it bears on the seat 3 and each time 110 the valve is shut or opened the disk grinds on the seat, thus keeping a smooth seating

surface at all times. The stems as shown are so arranged that there is a space for play between the bottom of the slot in the end of the stem 9 and the end of the flattened section of the stem 10 so that as the disk grinds or wears into the seat, the stem does not retard the disk 4 from always being seated against the seat 3.

I have also shown means for protecting that portion of the valve seat which is exposed through the port or ports of the valve disk when the valve is closed. 37 is a disk which forms the means for protecting that portion of the face of the valve seat which is exposed through the port or ports of the valve disk when the valve is closed. The four lugs 38 on the disk 37 slide into the four slots 39 in the face of the flanged end of the valve body section 2 to hold the disk 37 in place so that it will not revolve with the valve disk 36. The face of the valve disk 4 bears on the face of the seat disk 5. The side of the disk 37 which faces the valve disk 4 is faced off and bears on the back of the valve disk 4, this back side of the valve disk also being faced off. The valve disk revolves and bears on the valve seat and the disk 37 bears on the back of the valve disk 4 by pressure entering at the inlet end of the valve body. The lugs 38 loosely fit into the slots 39 so that the disk 37 will follow the valve disk 4 when it wears either on its face or its back or wears into the valve seat, thereby scale, grit or other matter cannot enter the port of the valve disk when the valve is closed and attack or affect the faced surface of the valve seat.

The protecting plate 37 may also perform the functions of a valve seat in case of any back pressure entering the valve through the discharge chamber. Under such circumstances the back pressure will move the disk 4 together with the protecting plate 37 to the left in Fig. 1, and the plate 37 will then bear against shoulder 42 shown clearly in Fig. 2. Thereby the protecting plate 37 will act as a valve seat, the disk being revolved against it. The lugs 38 engaging grooves 39 prevent the plate 37 from rotating and the jointed valve stem will permit the disk 4 to move backward against plate 37.

Obviously, some features, parts, or construction may be used without others and in combination with others and my invention may be embodied in widely varying forms.

Therefore, without limiting myself to the construction and arrangement and combinations of parts as shown and described and without enumerating equivalents, I claim and desire to obtain by Letters Patent the following:

1. In a valve, the combination of a casing providing inlet and outlet chambers, a valve

seat having at least one aperture through it and faced on the side toward the inlet chamber, a valve disk on the inlet side of said valve seat and having at least one aperture through it, and a valve seat protecting plate free to move against said valve disk and held from rotation therewith.

2. In a valve, the combination of a casing providing inlet and outlet chambers, an apertured valve seat faced on the side toward the inlet chamber, an apertured valve disk on the inlet side of said valve seat, and a valve seat protecting plate free to move against said valve disk and held from rotation therewith, the said plate forming a valve seat when the normal direction of flow through the valve body is reversed.

3. In a valve, the combination of a casing providing inlet and outlet chambers, a valve seat having at least one aperture through it and faced on the side toward the inlet chamber, an apertured valve disk on the inlet side of the said valve seat suitably mounted in the said valve casing and suitably engaged by an operating stem to permit of it being slidably movable forward and backward, a valve seat protecting plate upon the inlet side of the said valve disk and provided with at least one port registering substantially with at least one aperture of the said valve seat and mounted so as to be slidably movable forward and backward, and means to hold the said protecting plate against rotation, the said protecting plate and the said valve disk having relative movement forward and backward in the valve casing, the said protecting plate adapted to form a valve seat when the normal direction of flow through the valve body is reversed.

4. A valve comprising a casing having inlet and outlet chambers, a valve seat having at least one aperture through it and faced on the side toward the inlet chamber, an apertured valve disk on the inlet side of said valve seat, and a valve seat protecting plate adjacent said disk and having at least one port registering substantially with at least one port of said valve seat and mounted in the said valve casing so as to be slidably movable forward and backward.

5. A valve comprising a casing having inlet and outlet chambers, a valve seat having at least one port through it and faced on the side toward the inlet chamber, an apertured valve disk on the inlet side of said valve seat suitably mounted in the said valve casing and suitably engaged by an operating stem to permit of it being slidably movable forward and backward and to permit of it being revolved clockwise and anti-clockwise, and a valve seat protecting plate adjacent said disk and having at least one port registering substantially with at least one port of said valve seat.

6. A valve comprising a casing having inlet and outlet chambers, a valve seat having at least one aperture through it and faced on the side toward the inlet chamber, a valve disk on the inlet side of said valve seat and having at least one aperture through it, a valve seat protecting plate adjacent said disk and having at least one aperture through it registering substantially with 10 at least one aperture of said valve seat and mounted in the said valve casing so as to be slidably movable forward and backward, and means to hold said protecting plate against rotation.
15. 7. A valve comprising a casing having inlet and outlet chambers, a valve seat having at least one aperture through it and faced on the side toward the inlet chamber, an apertured valve disk on the inlet side of 20 said valve seat suitably mounted in the said valve casing and suitably engaged by an operating stem to permit of it being slidably movable forward and backward and to permit of it being revolved clockwise and anti- 25 clockwise, a valve seat protecting plate adjacent said disk and having at least one port registering substantially with at least one aperture of said valve seat, and means to hold said protecting plate against rotation.
30. 8. A valve comprising a casing having inlet and outlet chambers, an apertured valve seat faced on the side toward the inlet chamber, an apertured valve disk on the inlet side of 35 said valve seat suitably mounted in the said valve casing and suitably engaged by an operating stem to permit of it being slidably movable forward and backward and to permit of it being revolved clockwise and
- anti-clockwise, and a valve seat protecting plate free to move against said valve disk 40 and held from rotation therewith.
9. A valve comprising a casing having inlet and outlet chambers, an apertured valve seat faced on the side toward the inlet chamber, an apertured valve disk on the 45 inlet side of said valve seat suitably mounted in the said valve casing and suitably engaged by an operating stem to permit of it being slidably movable forward and backward and to permit of it being revolved 50 clockwise and anti-clockwise, and a valve seat protecting plate free to move against said valve disk and held from rotation therewith, and mounted in the said valve casing so as to be slidably movable forward and 55 backward.
10. A valve comprising a casing having inlet and outlet chambers, an apertured valve seat faced on the side toward the inlet chamber, an apertured valve disk on the 60 inlet side of said valve seat suitably mounted in the said valve casing and suitably engaged by an operating stem to permit of it being slidably movable forward and backward and to permit of it being revolved clockwise and 65 anti-clockwise, and a valve seat protecting plate free to move against said valve disk and held from rotation therewith, and mounted in the said valve casing so as to be 70 slidably movable forward and backward, the said protecting plate forming a valve seat when the normal direction of flow through the valve body is reversed.

In testimony whereof I have signed this specification.

OWEN MARSHALL JONES.
